UNITED STATES PATENT OFFICE.

ABRAHAM BIVINS, OF DENVER, COLORADO.

WRENCH.

SPECIFICATION forming part of Letters Patent No. 703,377, dated July 1, 1902.

Application filed April 22, 1902. Serial No. 104,150. (No model.)

To all whom it may concern:

Be it known that I, ABRAHAM BIVINS, a citizen of the United States, residing at Denver, county of Arapahoe, and State of Colorado, 5 have invented a certain new and useful Improvement in Wrenches, of which the following is a specification.

My invention relates to a new and useful improvement in wrenches, and has for its object to provide a wrench so constructed that the movable jaw can be moved downward by a simple downward pressure of the same to remove it quickly from the nut, but when the pressure is released the lower jaw will spring 15 back to the same position and be held in that position until it is desired to again lower the same, or by the insertion of a single screw the wrench can be used the same as an ordinary monkey-wrench.

With these ends in view this invention consists in the details of construction and combination of elements hereinafter set forth and then specifically designated by the claims.

In order that those skilled in the art to 25 which this invention appertains may understand how to make and use the same, the construction and operation will now be described in detail, referring to the accompanying drawings, forming a part of this specification, in 30 which—

Figure 1 is a vertical sectional view of the handle of the wrench, all other parts being shown in elevation. Fig. 2 is a section on the line 2 2 of Fig. 1; Fig. 3, a section on the 35 line 3 3 of Fig. 2.

A represents the handle of the wrench, which is of the same general outline as an ordinary wrench - handle; but this handle is made hollow.

B represents the fixed jaw of the wrench, which is formed upon the upper end of the shank C, which extends downward into the handle and is secured to the handle by means of the rivet D', which passes through the handle and also through the shank.

D is the movable jaw, which surrounds the shank C at the rear, and this movable jaw D has formed with it a screw-threaded extension E, extending downward from it and 45 adapted to slide within a V-shaped groove formed in the forward edge of the shank C, as shown in Fig. 3.

F represents two slide-bars, one arranged upon each side of the shank C, and these slide-bars extend downward into the handle 55 of the wrench, and each is slotted, as indicated at G, through which slot passes the rivet D', which fastens and pivots the shank C to the handle.

H is a gnarled or milled interiorly-threaded 60 nut which surrounds the shank C and the slide-bars F and also the screw-threaded extension E, upon which the nut is threaded. The slide-bars F are flanged at I above and below the nut, so that the nut really becomes a 65 part thereof, but can be rotated. J represents two cross-pieces secured to the handle upon the inside and extending across the same near the lower end. The lower end of the shank C extends downward between these 70 cross-pieces and terminates within a very short distance of the closed lower end of the handle. The shank C by being fastened to the handle at only one point is in reality pivoted upon the rivet D', and the handle is so 75 formed that this shank and everything carried by it will be allowed a limited amount of rocking movement upon the pivot.

K is a spring interposed between one wall 80 of the handle and the front face of the shank at a point below the pivot. Thus this spring will always hold the shank in its straight or normal position, and when in this position the lower end of the slide-bars F will lie 85 within a step L, formed in each of the cross-pieces J.

When the shank is in its straight or normal position, as shown in Fig. 1, by turning the nut H the movable jaw D can be moved toward and away from the fixed jaw B, the same 90 as an ordinary monkey-wrench, the nut being held stationary, because of the fact that it is held between the flanges I of the slide-bars F, and said slide-bars are prevented from upward movement by the lower end of the 95 slot G coming in contact with the rivet D', and said bars are prevented from downward movement by reason of their lower ends abutting against the step L of the cross-pieces J; but when it is desired to remove the 100 wrench from the nut to secure a new hold upon the nut or for using the wrench upon another nut of the same size it is desirable to quickly loosen the jaws without revolving

the nut H and when applied to the nut again to have the movable jaw resume its original position. This I accomplish by pressing the upper end of the wrench rearward, as shown 5 in dotted lines in Fig. 1, and this movement will bring the lower end of the slide-bars F forward of the step, which will allow the nut H, movable jaw G, and slide F to be pushed downward, because of the fact that the lower 10 end of the slide-bars will then be over the cut-away portion M of the cross-pieces J. This downward movement of the movable jaw will release the wrench from the nut; but after the wrench has been applied to new faces upon 15 the nut or upon a new nut of the same size by releasing the pressure upon the nut H the spring N, which is interposed between the lower flanges I of the slide-bars and the upper end of the handle, will return the parts 20 to their original position, and the spring K will then act to press the shank C back into its straight or normal position, which will bring the lower end of the slide-bars again within the steps L of the cross-pieces J.

25 This wrench can be used to great advantage in places where a full turn cannot be made with the wrench and the wrench has to be released a number of times before the nut is tightened, or it can be used to great advantage upon vehicles in taking off and putting on the wheels when the nuts are all of the same size.

When it is desired to convert the wrench into an ordinary monkey-wrench, so that the 30 movable jaw D cannot be raised and lowered without revolving the nut H, I provide through the lower end of the handle A a screw O, the inner end of which is inserted in a small nut P, which will lie in front of the lower end of 35 the shank C, and said screw when pushed in prevents any rocking movement of the shank upon its pivot.

40 Of course I do not wish to be limited to the exact construction here shown, as slight modifications could be made without departing from the spirit of my invention.

Having thus fully described my invention, what I claim as new and useful is—

1. In a wrench, a hollow handle, a fixed 45 jaw, a shank secured to said fixed jaw and pivoted at a point between its two ends to the upper end of the handle, a spring interposed between the handle and the front face of the shank, a movable jaw slidably mounted upon the shank, a screw-threaded extension extending downward from the movable 50 jaw, a nut threaded upon said screw-threaded extension, means whereby said nut and movable jaw can be slid downward upon the shank 55 60 when said shank is rocked upon its pivot, and a spring for returning said nut and movable jaw to their original position, substantially as and for the purpose specified.

2. In a wrench of the character described, a hollow handle, a fixed jaw, a shank secured 65 to said fixed jaw and pivoted between its two ends to the lower end of the handle, a movable jaw slidably mounted upon said shank, a screw-threaded extension extending downward from said jaw, two slide-bars, one arranged upon each side of the shank and provided with slots through which the pivot of the shank extends, a nut surrounding the upper end of the slide-bars, shank, and threaded upon the screw-threaded extension of the 70 movable jaw, flanges formed upon the slide-bars above and below the nut, a spring interposed between the lower flanges and the upper end of the handle, means for allowing the nut, slide-bars and movable jaw to be pressed 75 away from the fixed jaw when the shank is rocked upon its pivot, and a spring for returning the shank to its normal position, substantially as described and for the purpose specified.

3. In a wrench of the character described, a hollow handle, a fixed jaw, a shank secured to the fixed jaw and pivoted at a point between its ends to the upper end of the handle into which the shank extends, a movable jaw 90 slidably mounted upon the shank, a screw-threaded extension extending downward from the movable jaw, two slide-bars, one arranged upon each side of the shank and extending into the handle, said slide-bars provided with 95 slots through which passes the pivot securing the shank to the handle, an interiorly-threaded nut surrounding the upper end of the slide-bars also surrounding the shank and threaded upon the screw-threaded extension 100 of the movable jaw, flanges upon each of the slide-bars arranged above and below the nut, a spring interposed between the lower flanges and the upper end of the handle, a spring interposed between one of the walls of the 105 handle and the forward edge of the shank below the pivotal point of said shank, two cross-pieces secured upon the interior of the handle and extending across the same, one upon each side of the shank, a step formed in each 110 cross-piece in which the lower end of the slide-bars rest when the parts are in their normal position, a cut-away portion formed in each cross-piece for the reception of the slide-bars when the shank is rocked and the said slide-bars are pressed downward, and means for locking the shank in its straight or normal 115 position, substantially as described and for the purpose specified.

In testimony whereof I have hereunto affixed my signature in the presence of two subscribing witnesses.

ABRAHAM BIVINS.
